UNITED STATES PATENT OFFICE.

WILLIS R. WHITNEY, OF SCHENECTADY, NEW YORK, ASSIGNEE TO GENERAL ELECTRIC COMPANY, A CORPORATION OF NEW YORK.

VAPOR ELECTRIC APPARATUS.

No. 901,506.

Specification of Letters Patent.

Patented Oct. 20, 1908.

Application filed October 31, 1904. Serial No. 230,687.

To all whom it may concern:

Be it known that I, WILLIS R. WHITNEY, a citizen of the United States, residing at Schenectady, county of Schenectady, State of New York, have invented certain new and useful Improvements in Vapor Electric Apparatus, of which the following is a specification.

The invention herein described relates 10 more especially to vapor electric devices such as mercury vapor rectifiers, lamps, or the like.

The invention comprises certain improvements in the construction of apparatus of 15 the character mentioned, and its novel features are pointed out with particularity in the appended claims.

For a better understanding of the invention itself, both as to its details of construction and mode of operation, reference may 20 be had to the following description taken in connection with the accompanying drawing, which, by way of illustration, represents my invention as embodied in a single-phase mercury vapor rectifier.

The exhausted envelop of the rectifier, preferably of glass, may of course assume 25 a variety of shapes. In the form shown it consists mainly of a cylindrical vessel 1 having a depending contracted portion 2.

The negative electrode or cathode of the rectifier consists of a body of mercury 3 contained in a glass tube 4, the lower end of which is closed by an iron cap 5 sealed 35 about the same. This sealing operation is performed, while the parts are hot, by blowing the glass into contact with the metal and then allowing the same to cool. The metal then shrinks tightly about the glass and 40 being thin enough to stretch forms a tight joint therewith and without exerting a dangerous pressure upon the glass. About one one-hundredth of an inch is a suitable thickness of metal to employ. In a similar manner, an open-ended iron tube 6 is sealed 45 about the lower end of the depending member 2 of the rectifier and about the upper end of the glass tube 4, and thus holds the parts in position. The opposite ends of the tubes 2 and 4 do not come together but leave 50 a portion of the inner surface of the iron tube 6 exposed as at 7. This portion of the iron tube I utilize as a starting electrode.

The main positive electrodes or anodes of 55 the apparatus are contained in the lower

portion of the envelop 1 and consist of thin metal caps 8 and 9 sealed respectively about the lower ends of the reentrant tubes 10 and 11 forming a portion of the walls of the rectifier envelop. These iron caps are sealed 60 about the tubes in a manner already described with respect to cap 5. The lower ends of the tubes 10 and 11 are open so as to afford access to the inner ends of the caps. Bodies of mercury are contained in the tubes 65 as at 12 and 13, and thus make contact with the exposed portions of said caps.

Electrical connection with the anodes is conveniently made by means of metal tubes 14 and 15 extending axially along the glass 70 tubes 10 and 11 and dipping into the bodies of mercury 12 and 13. These tubes 14 and 15 perform not only the function of current-conveying leads for the apparatus, but serve also as conduits to circulate cooling 75 fluid down the tubes to the anodes to cool them and the adjacent parts and prevent them from reaching excessive temperatures. To this end the pipes 14 and 15, where they dip into the mercury, are open both at their 80 lower ends and also at the holes punched as at 16 and 17. These tubes 14 and 15 pass up into the lower ends of vertically arranged pipes 18 and 19 and then out through the walls of the same to a radiator 85 consisting of numerous turns of pipe as at 20. The continuation of each pipe 14 and 15 is thus coiled to form a radiator and finally passes into the top of the respective pipes 18 and 19. Two independent fluid-circulating systems are thus provided.

As the apparatus operates, heat is conveyed to the fluid, such as water, surrounding for example the pipe 14, and the fluid thereupon rises and passes up through the 95 pipe 18 which, of course, is fitted through a stopper or other connection into the upper end of the tube 10. The heated fluid, continuing to rise, causes the colder fluid in the external pipe 20 to be drawn through the 100 inner tube 14 and discharged through the openings in the lower end thereof. The anode 12 is thus kept relatively cool, while the walls of the tube 10 being also cooled serve in a large measure as a condensing 105 means for surplus mercury vapor in the apparatus. A similar circulation of fluid takes place in the other tube 11 so that no special description thereof is necessary.

In connecting up the apparatus for opera- 110

tion the single phase alternating supply leads, indicated at 21 and 22, are connected respectively to the tubes 14 and 15 and thereby to the anodes 12 and 13. The consumption circuit 23 of the rectifier is connected between the cap 5, with which the mercury cathode 3 makes contact, and the junction point 24 between two inductance coils 25 and 26 in series across the mains 21 and 22. This particular mode of operation is not new and requires no special description.

The starting electrode, consisting of the iron tube 7, is connected, during starting, through a resistance 27 to one of the alternating current supply leads such as 22. When the switch 28 in the starting electrode circuit is closed and the apparatus is shaken so as to cause the mercury 3 to make temporary contact with the inner wall of the tube 7 an initial arc is produced which, in a manner already known to those skilled in the art, causes the main arcs to start in the rectifier between the cathode and the main anodes 12 and 13.

It is evident that various modifications in the embodiment of my invention may be

made without departing from the spirit thereof, for which reason I do not wish to be limited to the details shown and described. 30

What I claim as new, and desire to secure by Letters Patent of the United States, is,—

1. In a vapor electric device, a glass member containing mercury, constituting one electrode, and a metal tube sealed about said member in proximity to said mercury and having an exposed portion constituting another electrode. 35

2. In a vapor electric device, a vitreous envelop formed in communicating parts, a metal shell tightly clasping the two parts so as to be under tension and so as to connect said parts so as to form an impervious joint therewith, a portion of the metal shell being exposed to form an electrode, and a co-operating electrode located in one of the parts of the envelop. 40 45

In witness whereof I have hereunto set my hand this 29th day of October, 1904.

WILLIS R. WHITNEY.
